Primary Examiner — Terry Wallace(74) *Attorney, Agent, or Firm* — Alexander D. Raring(57) **CLAIM**

The ornamental design for a juicer, as shown and described.

DESCRIPTION

FIG. 1 is a perspective view as seen from the top, front and right side of juicer showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any broken line illustration of the structure in the drawings is not part of the claimed design.
